CLAIM

The ornamental design for a cellular remote base unit, as shown and described.

DESCRIPTION

FIG. 1 is a top, front, and right side perspective view of a cellular remote base unit showing our new design;

FIG. 2 is a left side elevational view;

FIG. 3 is a bottom plan view; and,

FIG. 4 is a rear elevational view.

The broken line showings of a recessed region and locking mechanism in FIG. 4 are for illustrative purposes only and forms no part of the claimed design.

FIG. 1

FIG. 2

FIG. 3
